D17,576

UNITED STATES PATENT OFFICE.

HOLMES SMITH, OF ST. LOUIS, MISSOURI.

DESIGN FOR A COOKING-STOVE.

SPECIFICATION forming part of Design No. 17,576, dated August 2, 1887.

Application filed June 21, 1887. Serial No. 942,045. Term of patent 14 years.

To all whom it may concern:

Be it known that I, HOLMES SMITH, a British subject, residing at the city of St. Louis, State of Missouri, have invented and produced 5 a new and original Design for Cooking-Stoves, of which the following is a specification, reference being had to the annexed engraving, forming part thereof, and showing the newly-designed stove in perspective.

10 The stove A, so far as its general shape is concerned, is of a familiar type, its body *a* being cubiform, supported upon legs *a'*, having a hearth, *a²*, and at the opposite end having a reservoir, *a³*. This last-named part, however, 15 rests upon a bracket, *a⁴*. The leading feature of the design is an ivy ornamentation appearing upon the side of the stove, and more particularly described as follows: Upon the oven-door *a⁵* is an escutcheon, B, surrounded by a 20 wreath, C, of ivy, the wreath being extended at the left in the form of a spray, *c*, and terminating near the door-knob *c'*. Upon the reservoir is an ivy wreath, D. Upon the bracket beneath the reservoir is a sprig, E, of ivy, and 25 upon the fire-place door *a⁶* a cluster, F, of ivy leaves is shown. Upon the legs is a lion's face, G, terminating below in a leafy ornamentation, *g*, all substantially as represented in the engraving.

30 I claim—

1. The design for a cooking-stove herein shown and described, the same consisting of the wreath extended in the form of a spray, as described, upon the oven-door, the wreath upon the reservoir, the sprig upon the reservoir-bracket, and the cluster upon the fire-place door. 35

2. In a design for a cooking-stove, the oven-door herein shown, and provided with ornamentation consisting of the ivy wreath extended in the form of a spray. 40

3. In a design for a cooking stove, the reservoir herein shown, and provided with ornamentation consisting of the ivy wreath. 45

4. In a design for a cooking stove, the reservoir herein shown, and provided with ornamentation consisting of the sprig of ivy. 50

5. In a design for a cooking-stove, the fire-place door herein shown, and provided with ornamentation consisting of the cluster of ivy. 55

6. In a design for a cooking-stove, the shape and ornamentation of the legs, said ornamentation consisting of the lion's face terminating below in leafy work and having beaded work above the face. 60

HOLMES SMITH.
